(57) **CLAIM**

The ornamental design for a cartoning machine, as shown and described.

DESCRIPTION

FIG. 1 is a right front perspective view of a cartoning machine according to a first embodiment of the new design; FIG. 2 is a left front perspective view thereof;

FIG. 3 is front view thereof;

FIG. 4 is a rear view thereof;

FIG. 5 is a left side view thereof;

FIG. 6 is a right side view thereof;

FIG. 7 is a top view thereof; and,

FIG. 8 is bottom view thereof.

The broken lines show portions of the cartoning machine that form no part of the claimed design.
